JAR CLOSURE

William M. Robertson, Waterville, Ohio, assignor
to Owens-Illinois Glass Company, a corpora-
tion of Ohio

Application October 6, 1939, Serial No. 298,165

1 Claim. (Cl. 215—46)

The present invention relates to improvements in jar closures and more particularly to means for facilitating the removal of closures from vacuumized containers such for example, as fruit jars.

The difficulties encountered in opening vacuumized containers, fruit jars for example, are well known. They are largely due to the fact that the contents are packed hot and a considerable internal vacuum is created incident to cooling of the contents and container. Moreover, the sealing surface or finish of the glass container very frequently becomes coated with a portion of the liquid contents, with the result that the rubber sealing ring tightly adheres thereto.

An object of my invention is the provision of novel and efficient means whereby the sealing ring ordinarily employed in hermetically closing fruit jars and the like, may be removed from sealing contact with the finish or sealing surface of a glass container without resorting to the use of various implements such as are employed so frequently at present. To this end the invention comprises the formation of a tab at the outer margin of the sealing ring and the projection of this tab outwardly through a slot in the attaching flange, or skirt, of the closure proper. This tab is intended to be utilized by the consumer as a means for breaking the seal between the ring and sealing surface or finish of the container.

Other objects will be in part apparent and in part pointed out hereinafter.

In the drawing:

Fig. 1 is a fragmentary side elevational view of a jar and metal screw type closure embodying my invention.

Fig. 2 is a top plan view thereof.

Fig. 3 is a fragmentary vertical sectional view showing the ring in sealing position.

Fig. 4 is a fragmentary top plan view with parts broken away and disclosing the construction of the sealing ring.

Fig. 5 is a view similar to Fig. 3, illustrating the manner in which the seal is broken by pulling the tab on the sealing ring.

Fig. 6 is a top plan view partly in section illustrating substantially the shape assumed by the sealing ring incident to pulling of the tab.

The illustrated embodiment of my invention is shown in conjunction with a glass container 10 and a metal screw type closure 11. The container includes a circular wall 12 or neck defining a filling and discharging opening 13, said

wall terminating at its outer end in a relatively flat sealing surface or finish 14. External screw threads 15 are provided on the wall 12 for engagement with threads 16 which constitute a part of the attaching flange 17, or skirt, of the closure 11.

The closure 11 includes in addition to the attaching flange, a circular top 18 which may well include an annular stiffening bead 19. At the juncture of the top 18 and attaching flange, there is provided in the latter, a circumferentially extending slot 20 which is designed to accommodate a finger tab 21, the latter formed integral with a sealing ring 22. This sealing ring may be permanently attached to the inner surface of the top 18 of the closure for convenience. If preferred, the sealing ring 22 may be formed with recesses 23 at the juncture of the base of the tab 21 and the ring proper in order to facilitate pulling the tab and ring radially outward when it is desired to break the seal between the ring and container. The function of these recesses is obvious by reference to Figs. 4 and 6.

In view of the above, it is apparent that when it is desired to open a vacuumized hermetically sealed container of the type disclosed herein, it is only necessary to grip the tab 21 and pull it radially outward to substantially the position shown in Figs. 5 and 6. This results in breaking of the internal vacuum and therefore a material decrease in the external pressure upon the closure. The closure may then be removed from the container with ease.

Modifications may be resorted to within the spirit and scope of the appended claim.

I claim:

In combination, a container having a circular wall defining a filling and discharging opening and provided with a sealing surface at its outer end, a closure for the container adapted to be telescoped over said wall and including a top and depending attaching flange, said flange having a circumferentially extending slot substantially at its juncture with the top, a sealing ring interposed between the top and said sealing surface, and a finger tab provided on said ring and projecting outwardly through the slot, the base of said tab being of less width than the slot, said sealing ring also being reduced in transverse width at its point of juncture with the base of the tab in proximity to and inwardly from each end wall of the slot.
